USPC D13/107-110, 118-119, 184; D14/251, D14/253, 432, 434

The ornamental design for a battery charger, as shown and described.

CPC Y02E 60/12; Y02T 90/14; Y02T 90/122; Y02T 90/128; Y02T 90/163; H02J 7/025; H02J 7/0042; H02J 7/0044; H02J 7/0045; H02J 7/0003; H01F 38/14; H01R 13/6675; H01M 2/1022; H01M 2/1055; H01M 10/44; H01M 10/46; H01M 10/425; B60L 11/182

DESCRIPTION

See application file for complete search history.

FIG. 1 is a top right-front isometric view of a battery charger showing our new design.

(56) **References Cited**

FIG. 2 is a bottom left-rear isometric view thereof.

U.S. PATENT DOCUMENTS

FIG. 3 is a top left-rear isometric view thereof.

D203,543 S	1/1966	Coe
3,938,024 A	2/1976	Clarke
4,412,277 A	10/1983	Mitchell

FIG. 4 is a bottom right-rear isometric view thereof.

FIG. 5 is a top plan view thereof.

FIG. 6 is a bottom plan view thereof.

FIG. 7 is a front elevational view thereof.

FIG. 8 is a rear elevational view thereof.

FIG. 9 is a left side elevational view thereof; and,

FIG. 10 is a right side elevational view thereof.

The broken lines in the figures depict portions of the article which form no part of the claimed design.
